UNITED STATES PATENT OFFICE.

ROLAND W. BROWN, OF NEW YORK, N. Y.

SELF OPENING AND DELIVERING ENVELOPE.

Application filed December 1, 1921. Serial No. 519,126.

To all whom it may concern:

Be it known that I, ROLAND W. BROWN, a citizen of the United States, residing at New York city, borough of Manhattan, in the county of New York and State of New York, have invented certain new and useful Improvements in Self Opening and Delivering Envelopes, of which the following is a specification.

10 This invention relates to stationery and has particular reference to envelopes of the self-opening nature.

15 Among the objects of the invention is to provide an envelope with an insert either therein or to be furnished with the envelope for insertion thereinto, the insert being so arranged or constructed as to constitute a cutter or opener for the envelope in the hands of the person to whom it is addressed and 20 also as an ejector or deliverer for the letter sheet or message, the opening of the envelope and the delivery of the message sheet or carrier being accomplished by a single simple pull of the insert from the envelope.

25 With the foregoing and other objects in view the invention consists in the arrangement and combination of parts hereinafter described and claimed, and while the invention is not restricted to the exact details of 30 construction disclosed or suggested herein, still for the purpose of illustrating a practical embodiment thereof reference is had to the accompanying drawings, in which like reference characters designate the same 35 parts in the several views, and in which—

Figure 1 is a face view of one form of my improvement with the insert indicated in normal carrying position in the envelope ready to be pulled for delivering the message or message carrier.

40 Fig. 2 is a face view of the insert and message carrier separated from the envelope.

Fig. 3 is a transverse section on the line 45 3—3 of Fig. 2.

Referring now more specifically to the drawings, I indicate at 10 an envelope which in general construction or design may be similar to any well known envelope 50 and which may be provided with a window at 11 if desired, but which is not claimed herein. The only departure from any standard envelope is in the provision of an open notch 12, shown as a semi-circle and 55 located preferably at the center of one end of the envelope. This notch might be

located elsewhere, but for most convenience and best results I locate it as indicated.

The above mentioned insert is indicated at 13 as being a simple flat sheet of paper 60 or the like of a weight or quality which for practical purposes may be no heavier or better than the stock of the envelope. Generally speaking the insert is rectangular but is provided with an end 13^a in the form of 65 a trapezoid. In other words this end is provided with two beveled or inclined edges 14 serving as cutters for the end 15 of the envelope, while between the cutting edges 14 is a point portion 16 of any suitable 70 specific shape and which may be printed or otherwise furnished if desired with the legend "Pull here." This point portion 16 lies exposed in the notch 12 of the envelope after being inserted thereinto in the usual 75 manner through the open flap of the envelope and after which the sealing flap will be sealed as usual for first class mail. Obviously for open or inspection mail the closing of the envelope may be performed in 80 any customary manner, and my improved 85 opener and message deliverer will operate just the same as in connection with sealed or first class mail. On the opposite end of the insert 13 from the point 16 I preferably 90 provide a notch or recess 17, which for economy of material may be a counterpart of the point portion aforesaid so that there will be practically no waste of material in cutting these inserts as indicated by the dotted lines at 18, Fig. 2. The purpose of this 95 recess 17 is to insure clearance within the end of the envelope where it will be grasped by the thumb and finger of one hand while the point 16 of the insert will be grasped and pulled by the thumb and finger of the 100 other hand, thus insuring that the end holding the envelope will not grip the insert while the cutting of the envelope and the delivery of the message carrier take place.

As one becomes familiar with the ease and effectiveness of the device as an opener, the notch or recess at 17 is not essential. Except for the features of construction described above, the insert is preferably made to substantially fill the envelope as to length and width.

While in some instances the insert may constitute in itself a message carrier, for use in connection with letter sheets or circular material, I suggest the use of a slot 19 formed longitudinally along the insert 110

and at any desired portion thereof, as adjacent to one edge, and through which a portion of the folded sheet, as shown at S, may be passed and which together with the insert will be slipped into place in the envelope before sealing. When the insert is pulled as indicated with the fingers of one hand, the envelope being held with the fingers of the other hand, the cutting edges 14 cut directly through the end edge, 15 of the envelope throughout the width of the insert, and the message carrier or sheet S being threaded through the slot will naturally be drawn from the envelope at the same time or in the same movement and thereafter is easily separated from the insert which may then be discarded along with the used envelope. The insert may be made

if desired of a better quality of material and may be preserved for repeated use. 20

I claim:

The herein described envelope cutting insert comprising a substantially rectangular sheet of material to approximately fill the envelope to be opened thereby, but having at one end two beveled edges and having remote from said end means for making positive engagement with the message sheet for the delivery thereof coincident with the cutting open of the envelope, the means for engaging and delivering the message sheet being a slot formed through the insert. 25 30

In testimony whereof I affix my signature.

ROLAND W. BROWN.
